UNITED STATES PATENT OFFICE.

GEORGE C. BECKSTEIN, OF BUFFALO, NEW YORK.

DESIGN FOR A RING.

Application filed April 26, 1927. Serial No. 21,728. Term of patent 7 years.

To all whom it may concern:

Be it known that I, GEORGE C. BECKSTEIN, a citizen of the United States, residing at Buffalo, in the county of Erie and State of New York, have invented a new, original, and ornamental Design for a Ring, of which the following is a specification, reference being had to the accompanying drawing, forming a part hereof.

Figure 1 is an edge elevation of the ring showing my new design.

Figure 2 is a side elevation of the ring showing my new design.

Figure 3 is a top plan view of the ring showing my new design.

What I claim is:

The ornamental design for a ring, as shown.

GEO. C. BECKSTEIN.
